CAN OPENER

Samuel J. Mann, Englewood, N.J., assignor to Westinghouse Electric Corporation, Pittsburgh, Pa.

Filed Oct. 14, 1971, Ser. No. 189,486

Term of patent 14 years

Int. Cl. D7—04

U.S. Cl. D8—36

FIG. 1 is an isometric view of a can opener embodying my new design showing the top, one side, and front;

FIG. 2 is a front elevational view;

FIG. 3 is a side elevational view, the opposite side being a mirror image without the handle and slot therefor;

FIG. 4 is a rear elevational view; and

FIG. 5 is a top plan view.

I claim:

The ornamental design for a can opener, as shown and described.
